MISSOURI, ASSIGNEES TO FRANK W. BUFFUM, OF LOUISIANA, MISSOURI.

STENCIL-CARD-FEEDING ATTACHMENT FOR TYPE-WRITERS.

1,140,518.

Specification of Letters Patent. Patented May 25, 1915.

Application filed March 22, 1913. Serial No. 756,131.

To all whom it may concern:

Be it known that we, ALFRED L. McCAWLEY and WILLIAM W. PHILLIPS, citizens of the United States, residing, respectively, in Jefferson City and St. Louis and State of Missouri, have invented new and useful Improvements in Stencil-Card-Feeding Attachment for Type-Writers, of which the following is a specification.

10 This invention relates to a stencil card feeding attachment for typewriting machines, and has for its general object to provide a device of this character which shall be simple and reliable in operation and 15 which may be readily attached to a typewriter to permit of the use of the latter for the purpose indicated. The preferred embodiment of the invention shown in the drawings is intended for application to the 20 well-known Underwood typewriting machine, and is illustrated in the drawings as so applied.

It should be explained that the stencils referred to are usually about four and one-half inches long by two inches wide. They 25 comprise a central rectangular field of thin paper or similar material which is inclosed around its edge-portion by two thicknesses of paper, and these in turn are inclosed 30 at their edge-portion by two thicknesses of paste board, constituting a frame. The central field of thin tissue paper, or the like, is adapted to be moistened and when written upon by a suitable machine the type punctures the paper or so reduces its thickness 35 at the points of impact that it is rendered capable of use in the manner of a stencil. That is to say, by passing an ink roller over this thin field the ink will penetrate through 40 the portions weakened or punctured by the type and make an imprint on an envelop, card, or the like, placed beneath the stencil. These stencils are employed for addressing purposes, and are used by publishers, advertising agencies, large commercial houses, and 45 the like, where thousands of pieces of addressed mail matter are sent out at certain intervals. Heretofore it has been customary to employ special machines for preparing 50 these stencils, the ordinary typewriting machine not being adapted for this purpose. That is to say, the platen of the typewriter being round the stencil is bent or curved transversely upon being written upon; and 55 this very often renders the stencil incapable

of use in the automatic machines in which they are placed for the subsequent addressing operation.

According to our invention the stencil may be readily inserted in an upright position in the machine, and may be written upon and elevated for each new line by turning the platen roll in the ordinary manner, the stencil as a whole being maintained throughout in an upright position and prevented from being bent or curved in either direction.

In the accompanying drawings—Figure 1 is a plan view of a typewriting machine having our invention applied thereto, the ribbon and ribbon-carrying mechanism being removed; Fig. 2 is a view in front elevation of the same; Fig. 2^a is a sectional view on an enlarged scale of the upper portion of one of the adjustable posts which carries the 75 stencil-supporting bar; Fig. 3 is a view in end elevation, a portion of the machine being broken away, and our attachment and the parts of the machine immediately co-operating therewith being shown in section. 80

Referring now to the drawings, the numeral 1 indicates, generally, the frame of the typewriter, 2 the keys thereof, 3 the type-bars, pivotally mounted at their inner ends in the segment 4, and carrying at their outer ends types 5.

The numerals 6 indicate the end members of the platen-carrying frame, and 7 the platen rotatably mounted therein and adapted to be rotated by ratchet mechanism actuated by the ordinary return-lever, or by means of turning the milled heads 8 mounted on the ends of the platen shaft. We will here state that all of the parts of the typewriter shown are of the ordinary construction and only those parts will be referred to in this description which are necessary to make the application of our invention clear. 95

We will further state that before using our invention in addressing stencils it is necessary to remove the ribbon and ribbon guide. This is merely by reason of the particular construction of the machine under consideration, as the location of the ribbon guide in the commercial Underwood machine prevents the insertion of a stencil to the requisite distance in a straight line. 100

The preferred form of our attachment, as illustrated in Figs. 1, 2, 2^a, and 3, will now be described. 110

The numeral 9 indicates a plate which is of the length of the carriage of the type-writer and is provided at its ends with slots 10 through which headed screws 11 are adapted to be inserted and screwed into apertures in the frame members 6 at opposite ends of the carriage. At the front of the plate 9 there is a depending flange portion 12 which is vertically-disposed with its lower edge located in close proximity to the surface of the platen roll 7. This flange 12 acts as a guide, and as a support for the upper edge portion of the stencil to maintain it in a vertical position at all times while it is in the machine. Mounted on the plate 9 are two similar guide plates 13, each of which has at the front vertically-disposed flange portions 14 which extend downward parallel to the flange portion 12 and serve as guides for the ends of the stencil. Each of the plates 13 is provided with a longitudinal slot 15 through which passes a set screw 16 which enters a screw-threaded aperture in the plate 9. The plates 13 are preferably bent at a right angle at their rear edge to form a flange 13a which abuts against the rear edge of the plate 9 and thereby assists in maintaining the plates and guides in correct position. By loosening the set screws 16 and adjusting the plates 13 toward or from each other the space between the guides 14 may be lengthened or shortened to accommodate various sizes of stencils or cards. The numerals 17 indicate two similar spring arms which are secured to the rear edge of the plates 13, as indicated at 18, and each of which is bent twice upon itself at substantially right angles to form a depending arm 19 in the bottom or free end of which is journaled a feed roller 20 of rubber or like material. The rollers 20 are positioned directly opposite the platen roller 7, and in the horizontal plane of the axis thereof, and normally the spring arms 19 force these rollers into contact with the platen. Slidably mounted in sleeve bearings 21 near the outer ends of the plate 9 are two posts 22 each of which is normally pressed downward by a coil spring 23 interposed between a collar 24 thereon and the lower sleeve bearing 21. The upper end of each of these posts is screw-threaded, as indicated at 25, and has applied thereto an adjusting nut 26. The upper portion of the edge of the posts 22 is flattened at one side as indicated at 27, and graduation marks 28 are provided on this flat side. The posts 22 are connected at their lower ends to opposite ends of a bar 29 which is L-shaped in cross section, the foot 30 thereof serving as a support for the stencil. What we have termed herein as the segment-brace is shown in Fig. 1, and indicated by the numeral 31. In order to permit the stencils when inserted in the attachment to drop low enough to permit the maximum number

of lines to be written on the stencil field, we may provide the segment-brace 31 with a longitudinal groove 32, which, in practice, extends a short distance beyond each side of the sector 4. This groove 32 is wide enough to accommodate the bar 29 which normally rests on the bottom of the groove. This groove, however, may be dispensed with, especially when the later model of stencil-card is used, as with this type of card it is unnecessary to provide for the drop of the stencil-cards lower than the top of the segment brace. In order to move the feed rollers 20 a short distance away from the platen 7 to permit the insertion of a stencil we provide a flat bar 33 having cylindrical ends mounted in bearings 34 on the plate 9 and provided at one end with a push-lever 35. The bar 33 extends under and in contact with the horizontal portion of the spring arms 17, and by pressing the lever 35 backward the arms 19 are thereby thrown slightly outward permitting the ready insertion of the stencil between the guides 14, and between the rollers 20 and the platen 7, the stencil falling into the groove 32 and resting upon the foot 30 of the bar 29. When the lever 35 is released, the spring of the arm 17 turns the bar 33 to normal position. As shown by Figs. 1 and 2, when the stencil, which is indicated by 36, is in position the feed rollers 20 rest against the end portions 37 of the frame thereof and press it into contact with the platen 7 but without bending the frame, by reason of the fact, as previously stated, that the rollers 20 lie in the horizontal plane of the axis of the platen. In this position the field 38 of the stencil is in such position that the type will strike near the upper edge thereof, or practically along a line extending between the centers of the rollers 20. By manipulating the platen in the usual way, or by turning it by means of the milled heads 8, the stencil will be raised by frictional contact with the platen caused by the pressure of the feed rollers 20 on the stencil which pressure is in turn caused by the spring action of the arms 19. As each line is written the stencil is moved up the required space for a new line, and this continues until the entire number of lines, three or four, have been written, when the stencil is removed and a new one inserted. If only three lines are to be written on the stencils the adjusting nuts 26 are turned to bring the upper graduations 28 in line with the top of the nut, which action raises the bar 29 a given distance; and if only two lines are to be written the adjusting nuts 26 are turned to bring the lower graduation mark to position, which action raises the bar 29 a still farther distance, but not so much as to withdraw it from the groove 32 if the latter be employed, which then not only provides means for

accommodating the stencil in the machine, but also acts to maintain the proper alignment of the bar 29 with the guides 14. The plate 9 is recessed on its front side to form 5 near its ends shoulders 39 which limit the distance to which the guide plates 14 may be separated. The springs 23 not only serve to maintain the bar 29 in a horizontal position, but they also permit the said bar or 10 the posts 22 to yield in the event a slight depression of the carriage should tend to cause the bar to bind against the bottom of the groove 32.

While we have shown the best forms of 15 our invention now known to us, and have illustrated the same as applied to an Underwood typewriter, we wish to be understood as not limiting ourselves either to the precise construction and arrangement of parts described, or to the use of our invention with 20 an Underwood typewriter only except where we have so indicated in the claims.

We claim:

1. A stencil-card feeding attachment for 25 typewriters comprising a member adapted to be mounted on the machine and carrying feed-rollers, and a pair of vertical guides depending from said member that are provided with continuous flange portions be- 30 tween which the stencil-card passes as it is inserted in the device.

2. A stencil-card feeding attachment for 35 typewriters comprising a member adapted to be mounted on the machine and carrying feed-rollers, a pair of guides depending from said member and between which the stencil-card passes as it is inserted in the de- 40 vice, and a stencil support carried by and extending between said guides and adapted to have the lower edges of the stencil-cards rest thereon.

3. A stencil-card feeding attachment for 45 typewriters comprising a member adapted to be mounted on the machine and having a vertically-disposed flange depending there- from to serve as a support for the back of

the stencils, feed-rollers carried by said member for holding the stencils in feeding contact with the platen of the machine, and guides for the ends of the stencils depend- 50 ing from said member and located in a vertical plane in advance of said flange.

4.. A stencil-card feeding attachment for typewriters comprising a member adapted to be mounted on the machine and affording 55 a support for the back of the stencil, a pair of guides mounted on said member between which the stencil is adapted to be inserted, a pair of feed rollers mounted on said mem- 60 ber for holding the stencil in feeding con- tact with the platen of the machine, and a horizontally-disposed stencil support pend- ent from said member.

5. A stencil-card feeding attachment for typewriters comprising a supporting plate 65 for attachment to a machine, a pair of guide plates mounted thereon, a stencil support carried by said supporting plate, a pair of feed rollers mounted on said supporting plate for holding the stencil in feeding con- 70 tact with the platen of the machine, and means mounted on said supporting plate for moving at will the feed rollers away from the platen when the attachment is in posi- 75 tion on the machine.

6. A stencil-card feeding attachment for typewriters comprising a plate having a downwardly extending supporting flange for the back of the stencil, a pair of verti- 80 cally disposed guide members adjustably mounted on said plate, a pair of yielding feed rollers carried by said plate, and a horizontally-disposed stencil support also carried by said plate.

In testimony whereof we have hereunto 85 set our hands in presence of two subscr- ing witnesses,

ALFRED L. McCAWLEY.
WILLIAM W. PHILLIPS.
